UNITED STATES PATENT OFFICE.

THOMAS O. PERRY, OF CHICAGO, ILLINOIS.

AIR-COMPRESSOR.

No. 901,555.

Specification of Letters Patent.

Patented Oct. 20, 1908.

Application filed August 29, 1904. Serial No. 222,653.

To all whom it may concern:

Be it known that I, THOMAS O. PERRY, a citizen of the United States, residing at No. 1025 Park avenue, Chicago, in the county of 5 Cook and State of Illinois, have invented new and useful Improvements in Air-Compressors, of which the following is a specification.

This invention relates to improvements in 10 air compressors and pumps to be operated by variable power and more especially by wind power and to utilizing energy which is largely wasted in the ordinary use of windmills.

An ideal condition for utilizing wind power 15 in pumping might be realized if the diameter of the piston could be made to change in the same proportion that the velocity of wind changes, or if, without changing diameter of piston, the length of stroke could be made to 20 vary as the square of the wind's velocity.

The main object of my invention is to effect, without actually changing the diameter of the piston or the length of the stroke, by positive mechanism a variation in the 25 quantity of work per stroke of an air compressor or pump so that a windmill operating the same may within limits carry a load which shall automatically vary to correspond approximately with the changing 30 force of the wind.

Figure 1, is an elevation showing in general on a reduced scale the windmill with compressor attached and a portion of the supporting tower; Fig. 2, is a plan of the 35 head or cap of the air compressor. Fig. 3, is a sectional elevation of the air compressor on the line 3—3 of Fig. 2. Fig. 4, is a plan of the plunger packing showing the plunger in section. Fig. 5, is an exterior side elevation 40 of the compressor with vent regulator attached viewed in the same direction as Fig. 3. Fig. 6, is an exterior front elevation of the air compressor with vent regulator shown partly in section. Fig. 7, is a front elevation of the 45 compressor head with a modified form of the vent regulator attached.

Similar letters refer to similar parts throughout the several views.

The compressor cylinder, E, has exterior 50 flanges both at its upper and lower ends. The cap, C, is secured to the upper end of the cylinder by screws entering the upper flange. The plunger, F, fits the interior of cylinder, E, loosely, is closed at its upper end, 55 protrudes from the lower end of the cylinder and carries at its lower extremity a cross-head, G.

Plunger rods, G², rigidly connect the cross-head with the drive-head, G', which is adapted to reciprocate above the cap, C, and is centrally connected to the actuating rod, r, of 60 the windmill. This actuating rod, r, the windmill, B, D, K, P, R, S, V, and the supporting pipe, A, are the same as fully shown and described in my pending application for patent for windmill No. 102,608, filed April 65 12, 1902. A supporting plate, A', is secured to the lower end of the pipe, A, which supports the windmill at its upper end. Supporting guide rods, C², pass loosely through the drive-head and rigidly connect the cylinder cap, C, to the supporting plate, A'.

Surrounding the plunger and drawn to the lower cylinder flange by screws is a clamping ring, N, having an interior flange underneath loosely fitting the plunger, and inclosing together with the cylinder end an annular packing space. An elastic cylindrical packing, Q, exteriorly flanged on its under side surrounds and presses against the plunger within the annular space. A packing ring, 80 n, is interposed between the cylinder end and the exterior flange of the packing so that it binds the packing flange by tightening the clamping screws. Between the upper portions of the packing, Q, and packing ring, n, is 85 a thin annular recess adapted to receive packing-springs, q, which react between the packing-ring and elastic packing. These packing-springs are preferably arranged in two annular layers one within the other and each 90 layer made up of several thin flat spring sections. Four spring sections are shown in each layer in Fig. 4. The spring sections are all under tension. In the outer layer the ends of the spring sections press outward 95 against the clamping ring while their centers press inward against the ends of the spring sections in the inner layer which in turn press against the elastic packing throughout their length by reason of their proper form 100 before insertion and the superior stiffness of the outer spring sections. These spring sections may all be nearly straight before being sprung into the annular recess, or they may be curved before insertion as suits best the 105 tensions required when in place. The packing may be made of leather or other yielding material. The upper side of the clamping ring, N, loosely incloses an annular shoulder on the end of the cylinder of the same external diameter as the packing-ring, n. The 110 annular packing space is also adapted to re-

ceive other forms of packing such as are ordinarily used.

The cross-head, G, is not rigidly connected to the plunger, F, but is merely guided 5 loosely in its open lower end and is carried rigidly by a tie rod, L', whose upper end connects with a safety valve, L, which seats against and is guided in the upper closed head of the plunger. A powerful safety 10 spring, M, surrounding the tie rod, reacts between the closed head of the plunger and the cross-head so as to hold the safety-valve closed. The safety spring should have sufficient tension to drive the plunger without 15 yielding against any normal resistance, but is designed to yield to abnormal resistance such as might result from accidental clogging of the outlet or undue compression of air, so as to relieve the excessive pressure by letting 20 the safety-valve open. A very slight lifting of the safety-valve lets compressed air pass sufficiently to avoid dangerous pressure.

In the cylinder head is a check valve, J, opening outward, covered by a cap, O', from 25 which the outlet or delivery pipe, O, rises.

The intake valve, H, opens inward and is carried by and rests against a hollow cage, C', which screws into the cylinder head to one 30 side of the outlet. The guiding stem of the intake valve reaches up through the center of the cage and terminates in a knob, H', attached so as to form a shoulder beneath which a helical spring H² coiled around the stem and resting in a recess of the cage reacts 35 to balance the weight of the valve more or less. The under side of the knob, H', is guided in the recess and its upper part is enlarged so as to limit the vertical movement of the intake valve. Around the periphery 40 of the cage are openings for the passage of air.

As so far described, the compressor is complete for ordinary working, that is for taking in and discharging at each stroke a quantity of air equal to the area of the plunger multiplied by the length of stroke.

It remains to describe devices whereby the compressor is made to discharge into the delivery pipe varying quantities of air per stroke when the actuating power might 50 otherwise be overtaxed.

The contact lever, T, is hinged at one end to an adjustable fulcrum, U, movable vertically or parallel with the direction of the plunger's reciprocating motion. Between 55 its extremities the contact lever is adapted to rest upon the knob H', so as to prevent the intake valve closing. The other free end of the contact lever extends to within range of a catch, G³, carried by the drive head, G', so that it may be engaged and lifted by the 60 catch during the up or compressing stroke of the plunger. The intake valve is thus held open during the plunger's up stroke until permitted to close when the contact lever is 65 lifted by the catch. A round weight, T',

forms an enlargement of the contact lever where it rests on the knob. The free end of the contact lever will be elevated or depressed as the fulcrum is depressed or raised. So the closing of the intake valve will occur 70 earlier or later during the compression stroke according as the position of the fulcrum, U, is higher or lower. In order that the position of the fulcrum may be automatically adjusted to requirements, it is suspended from 75 a regulating piston, W, loosely fitting the regulating tube, V, closed at its upper end and secured to the supporting plate, A', by a neck, V', at its lower end. Passing loosely through the neck of the regulating tube is the 80 suspending rod, U', which unites the fulcrum, U, with the regulating piston, W. The lower end of the suspending rod, where the fulcrum is clamped on by means of a screw, is made 85 hollow so as to receive a guide, C⁴, reaching up from the compressor head, C. A shoulder, U², is so located on the suspending rod as to encounter a spur, G⁵, on the drive head, G', towards the end of each up stroke of the plunger, so that the regulating piston and 90 fulcrum may be raised to their upper limit of movement at the end of each compressing stroke.

As shown in Figs. 5 and 6, the movement of the regulating piston and fulcrum is limited to about one quarter the length of stroke given to the plunger. Within this limit of movement the regulating piston, W, descends by gravitation at a rate made practically uniform by reason of the partial vacuum formed above and the restriction to the flow of air past the loose fitting piston. The rate of the fulcrum's downward motion may be regulated by the fit of the piston in the regulating tube. The fulcrum may settle to 100 the limit of its downward movement if sufficient time elapses between the commencement of the down stroke of the plunger, F, and the completion of three quarters of its up stroke, as shown; in which case air will 105 freely escape by the intake-valve during three quarters of the plunger's up stroke, since the catch, G³, is so placed that it will not sooner lift the contact lever, T, and let the intake valve close when the fulcrum, U, 110 is at the limit of its movement downward. If the fulcrum, for want of time during quick strokes of the plunger, does not reach the limit of its downward movement, the intake valve will be closed earlier during the compressing stroke, and the quicker the stroke the earlier will it close until the fulcrum may settle so little that the contact lever will not rest on the knob at all and a full cylinder of air will be compressed at each stroke.

If the compressor be of such proportions that the windmill is properly loaded when compressing one quarter of its capacity per stroke in one velocity of wind, say eight miles per hour, it would require that full capacity 130

of air per stroke should be compressed in wind of double velocity, or sixteen miles per hour, in order that the load may also best suit the greater wind velocity. This condition is realized in the construction shown in Figs. 5 and 6, if for the one wind the adjustment is such that the full downward motion of the regulating piston, W , is reached at the moment when the compressing plunger, W' , has completed $\frac{1}{4}$ of its up stroke. Then in wind of double velocity, since piston speed is doubled and compression should begin with the commencement of the up stroke, the regulating piston has time to settle only $3/10$ as far as before. So the contact lever and catch are arranged to let the intake-valve close when the compressor plunger is at its lowest position and the fulcrum is at $3/10$ of its whole movement down. By means of an adjusting screw, and a by-pass, closed more or less by the screw, the rate of the regulating piston's descent may be increased or diminished.

A relief-valve, u , covering ports, in the regulating piston, W , allows air to pass freely only when the piston is forced up by the spur, G^5 , but this relief valve may be dispensed with since the regulating piston is sufficiently loose to let air pass quite freely around its periphery when forced up, although its descent by action of gravitation is relatively slow.

The above described intake regulating mechanism provides for closing the intake-valve when the plunger has completed $\frac{1}{4}$ of its compressing stroke, if the closing is not effected sooner. But the wind may weaken so much that its power becomes insufficient to force out even the minimum quantity of air which may be entrapped; in which case it is better to have the intake-valve remain open during the entire up stroke, in order that the wind-wheel, unresisted during the one stroke, may gain momentum to compress on the next or some succeeding stroke, or, so that, in case the wind-wheel stops on account of wind failure, it may start again unloaded by the compressor. To this end a latch, H^2 , carried by the intake-valve, H , has an end sloping upward and placed in the path of the traveling fulcrum, U , so that it may be pushed thereby under a spur, C^3 , on one of the guide-rods, C^2 , and hold the intake-valve open in case the fulcrum reaches the extremities of its downward movement, and not otherwise. A flexible cam, G^4 , carried by the drive-head, G' , is adapted to disengage the latch from under the spur at each down stroke, unless interfered with by extreme settling of the fulcrum. The latch, H^2 , is formed on one end of a bent wire, which passes through the valve knob, H' , and extends beyond so as to stop against the other guide-rod and limit its unlatching movement.

The intake regulating mechanism, as al-

ready described, involves a contact arm or lever shiftable with respect to the intake valve and a catch connected with the plunger so as to have corresponding reciprocating motion. Obviously a like result may be obtained by making the catch shiftable with respect to the plunger and having the contact arm conform only to the motion of the intake-valve. Also other means than a loose regulating piston may be used for shifting either the contact arm or the catch with respect to parts with which they are operatively connected.

The shifting movement of either contact-arm or catch must be of a different character from the regular motion of the parts with reference to which the shifting relates. A shifting movement adjustable with reference to the proper movement of either the plunger or intake-valve may be obtained by means of centrifugal weights driven either directly or indirectly by wind power. Such a device is illustrated in Fig. 7 in which the shifting mechanism is carried by the drive-head, G , and the catch, g' , shifts relatively to the plunger. A centrifugal governor of ordinary type has weights, Z , pivoted to a revoluble shaft, X , stepped in an extension, G^6 , of the drive-head, G' . The upper end of the governor shaft, X , is made square and is adapted to slide longitudinally through a sleeve, y' , fitting loosely thereon and which revolves as a journal in a bearing held by the bracket, A^3 , extending from the supporting pipe, A . A sheave, y , attached to the upper end of the journal, y' , may serve for imparting rotary motion to the governor shaft by means of a belt or other connection with the windmill. Or the governor shaft, X , may be driven by a separate horizontal wind-mill attached directly to the governor shaft. As shown, the horizontal wind-wheel consists of four hemispherical cups, Y , carried by four arms, Y' , radiating from the governor shaft, X , in the manner of ordinary anemometers. Links, z , connect the centrifugal weights, Z , with a swivel adapted to revolve upon and move longitudinally a slide-head, g^3 , guided on the governor shaft and carrying the catch arm, g . A guide rod, g^2 , attached to the catch arm parallel with and at some distance from the governor shaft passes loosely through the extension, G^6 , of the drive-head and prevents rotation of the catch, g' , terminating the catch arm. The catch arm is extended and bent so that its cylindrical end, g' , comes in line with the axis of the intake-valve, H . The contact arm in this case is forked, the two forks, t , being somewhat elastic and extending some distance up from the valve-knob, H' , to which they are attached so as to straddle the cylindrical catch, g' ; without touching except at their tips, which have beveled spurs facing each other with separating intervals somewhat less than the di-

ameter of the catch. This enables the catch, g' , to pass the spurs of arm, t , but not without contact sufficient to close the intake-valve, which in this case is normally held 5 open by gravitation.

It is evident that the governor will revolve with greater or less rapidity, according to the wind, and that the position of the catch, g' , with reference to the plunger, F , will be more 10 remote as the wind increases in velocity, with consequent earlier closing of the intake-valve. The catch, g' , in high wind, may shift far enough to close the intake at the 15 very beginning of the compressing stroke and in lower winds may close the intake after the plunger arrives within variable distances of the end of its stroke, which distances may vary all the way from that of full stroke to nothing. The adjustment of the shifting 20 intake governor depends on its relative speed of revolution, the proportion and arrangement of its various parts and upon such resistances to its centrifugal action as are ordinarily provided in governors of this character. The adjustment should be such that 25 the intake will close at the beginning of the compressing stroke in some determined velocity of wind, and at half that wind velocity the intake should not close until the plunger 30 completes $\frac{3}{4}$ of its compressing stroke. This form of the shifting intake governor is more especially adapted to use with power windmills or such as transmit their power through a vertical revolving shaft instead of by a reciprocating rod, and is just as adaptable to 35 shifting the contact arm with reference to the intake valve as to shifting the catch relatively to the plunger. Fig. 7 shows the drive-head, G' , in its lowest position and the 40 catch, g' , so placed by the governor as to encounter the contact spurs and close the intake when the plunger completes $\frac{3}{4}$ of its compressing stroke.

Another form of shifting intake regulator 45 is shown in Fig. 1. The forked contact arm, t , and the bent catch arm, g , terminating in a cylindrical catch, g' , are the same in form and operation as described above and shown 50 in Fig. 7; but the shifting of the catch relatively to the plunger in this case is accomplished in one direction by gravitation whose 55 action is retarded by the inertia of masses in great part counterbalancing each other through distribution on a pivoted lever fulcrum between its ends. The fulcrum is on a standard, G^7 , carried by an extension, G^6 , of the drive-head. The pivoted regulating lever, w , carries on one side of the fulcrum a mass, w' , and the catch arm, g , suspended 60 from its end by a link, while from its other end on the other side of the fulcrum hangs a mass, w^2 , suspended by a rod, w^3 , which passes loosely through a fixed arm, C^5 , extending from the compressor head, C . The 65 catch arm, g , is guided vertically on the ful-

crum standard and also by a pendent guide rod loosely passing through the drive-head extension, G^6 . The catch arm, g , and other parts composing the mass on one side of the fulcrum overbalance the mass on the other 70 side, so that the catch settles down whenever gravitation is free to act. The catch is restored during the last quarter of the plunger's compressing stroke to its highest position by engagement of the mass, w^2 , with the 75 fixed arm, C^5 , at intervals of variable duration depending on the velocity of wind. A stop on the rod, w^3 limits the upward movement of the catch. In light wind the catch will have time to settle nearer to the drive-head or plunger than in strong wind and will close the intake-valve later in the stroke as the wind becomes weaker.

In order that the intake may close so as to give the most efficient load in winds of different velocities, adjustments may be made by changing the relative moments of the counterbalancing masses and by altering the length of the contact arm, t . This device also can be substituted for the regulating 90 piston, W , to shift the position of the fulcrum, U .

Obviously the fulcrum, U , might be clamped upon the fixed guide rod, C^4 , instead of upon the movable suspending rod, U' , at any desired height and changed at will from time to time to suit varying winds or varying resistances to any applied power, and thus serve the same purpose that might, 95 with much greater inconvenience, be accomplished by using at different times various sizes of compressors or pumps or by changing the lengths of their strokes to suit changing conditions of power or work.

The above described devices for retaining 105 the vent or intake valve open during part of the compressing stroke serves also the purpose of moderating the interior temperature of the compressor which, on account of the heat generated in compressing air, reduces 110 efficiency and may seriously interfere with the proper lubrication and maintenance of the plunger packing.

Water cooling of the cylinder is not generally convenient in the class of work for which 115 this air compressor is designed; so air cooling becomes an important consideration. The vent or intake closing device enables a much larger compressor to be used than would otherwise be possible without overloading the wind mill or other actuating motor. This permissible enlargement of the compressor in itself furnishes an amount of radiating surface greatly increased in proportion to the average of work performed, 120 since it is only during the higher velocities of the ever varying wind that the compressor works to its full capacity, and during the frequent periods of reduced wind velocities a large amount of fresh air is taken in and ex- 130

5 pelled, without compression, serving thus to cool the interior of the cylinder where cooling is most needed. The substitution of a long plunger for the ordinary piston, and 10 making the plunger hollow, serves further to increase the radiating surface. The use of the long plunger also enables the plunger packing to be placed at the cool end of the cylinder farthest from the head where the 15 greatest heat is generated, thus rendering feasible the use of flexible packing material, such as leather, which otherwise might be burned out by the heat of compression.

15 While this invention is especially applicable to air compressors actuated by wind power, it may also apply to pumps for forcing other fluids, and may be used to advantage in connection with actuating motors other than windmills. For example, when 20 any kind of motor capable of carrying a certain constant load is unevenly loaded at intervals with other work, such as sawing wood or cutting fodder, this air compressor might, at the same time, be operated advantageously, because the air compressor could be so adjusted as to automatically compress more or less air per stroke, according to the 25 variations of motor power unconsumed by other work. When the other work might suffice to retard the motor to minimum speed desired, the intake would not close at all, and at a maximum of desired speed, when the load due to other work might be greatly reduced, full cylinders of air might 30 be compressed.

35 Air thus compressed may be stored in reservoirs for any desired purpose and especially for raising water by means of the device shown in my pending application for 40 patent for pneumatic pump, Serial Number 203,228, filed April 14, 1904.

What I claim as my invention, and desire to secure by Letters Patent, is—

1. The combination with a windmill and 45 an air compressor having a plunger with connected parts to which reciprocating motion is imparted by the windmill, of a vent valve by which air may escape during a portion of the compressing stroke, vent closing mechanism operative through contact with a reciprocating part, and means whereby the time of 50 said contact may be varied so that the vent may be closed after the plunger arrives within varying distances of the end of its compressing stroke, which distances vary with and are determined by the rate of the wind's velocity, substantially as herein set forth.

2. The combination with a windmill and 55 an air compressor having a plunger with connected parts to which reciprocating motion is imparted by the windmill, of a vent valve by which air may escape during a portion of the compressing stroke, vent controlling mechanism operative through contact with a 60 reciprocating part, and means whereby said

operative contact occurs when the plunger arrives within varying distances of the end of its compressing stroke, said varying distances corresponding to variations in the velocity of the wind, substantially as herein set forth. 70

3. The combination with a windmill and an air compressor having a plunger with connected parts to which reciprocating motion is imparted by the windmill, of a vent valve by which air may escape during a portion of 75 the compressing stroke, of a vent valve normally adapted to close, mechanism adapted to hold open and to retard the closing of the vent valve during part of the compressing stroke of the plunger, and means whereby 80 said retarding mechanism releases said vent valve when the plunger arrives within varying distances of the end of its compressing stroke, said distances being greater or less as the wind velocity increases or diminishes, 85 substantially as herein set forth.

4. The combination with a windmill and an air compressor having a cylinder and a reciprocating plunger operated by said windmill, of an intake-valve through which air 90 may also escape during a portion of the plunger's compressing stroke, and intake controlling mechanism whereby the closing of said intake-valve may be delayed until the plunger has arrived within variable distances 95 from the end of its compressing stroke which distances vary with and are determined by the rate of the wind's velocity, substantially as herein set forth.

5. The combination with a windmill and 100 an air compressor having a cylinder and a plunger operated by the windmill, of an intake-valve in the head of said cylinder through which air may also escape during a portion of the plunger's compressing stroke, 105 and intake controlling mechanism whereby the closing of said intake-valve may be delayed until the plunger arrives within varying distances of the end of its compressing stroke which distances vary with and are determined by the rate of the wind's velocity, 110 substantially as herein set forth.

6. The combination with a windmill and an air compressor having an intake-valve, a cylinder and a reciprocating plunger operated by said windmill, of mechanism whereby said intake-valve may be held open during part of the plunger's compressing stroke, and a releasing device to let the intake-valve close after the plunger arrives within variable 115 distances of the end of its compressing stroke which distances vary with and are determined by the rate of the wind's velocity, 120 substantially as herein set forth.

7. The combination with a windmill and 125 an air compressor having a plunger with connected parts to which reciprocating motion is imparted by the windmill, of a vent valve by which air may escape during a portion of the compressing stroke, and mechanism to 130

control the closing of said vent valve earlier or later in the compressing stroke of the plunger accordingly as the velocity of the wind increases or diminishes, substantially 5 as herein set forth.

8. The combination with a windmill and an air compressor having an intake-valve, an outlet valve, a cylinder and a reciprocating plunger operated by said windmill, of a retaining lever resting between its extremities upon 10 said intake valve to hold it open during part of the plunger's compressing stroke, a fulcrum at one end of said retaining lever movable in a direction parallel with the plunger's motion, 15 a catch reciprocating with the plunger and adapted to engage the other end of said retaining lever so as to release and close the intake valve during some part of the plunger's compressing stroke depending on the position 20 of said fulcrum at the time of engagement, and mechanism for automatically adjusting the position of said fulcrum so that at the time of engagement between said lever and said catch the intake valve may be 25 closed after the plunger arrives within variable distances from the end of its compressing stroke, which distances will vary with and be controlled by the rate of the rotation of the wind wheel, substantially as herein set 30 forth.

9. The combination with a windmill and an air compressor having a plunger with connected parts to which reciprocating motion is imparted by the windmill, of a vent valve 35 by which air may escape during a portion of the compressing stroke, vent closing mechanism ordinarily operative at variable distances of the plunger from the end of its compressing stroke, and means whereby the vent 40 valve may be locked and held open during the whole of the compressing when the motion of the windmill becomes excessively slow, substantially as herein set forth.

10. The combination with a windmill and 45 an air compressor having a plunger with connected parts to which reciprocating motion is imparted by the windmill, of a vent valve by which air may escape during a portion of

the compressing stroke, a vent closing lever operative through contact with a reciprocating part, and a movable fulcrum to said lever whereby said contact may be adjusted to close the vent valve at varying distances of the plunger from the end of the compressing stroke, substantially as herein set forth. 50 55

11. The combination with a windmill and an air compressor having a plunger with connected parts to which reciprocating motion is imparted by the windmill, of a vent valve by which air may escape during a portion of 60 the compressing stroke, a vent closing lever operative through contacts with a reciprocating part, a movable fulcrum to said lever, and means whereby the position of said fulcrum is adjusted automatically through the 65 action of the windmill, so that the vent valve may be closed when the plunger arrives at varying distances from the end of its compressing stroke, substantially as herein set forth. 70

12. The combination with a windmill and an air compressor having a plunger with connected parts to which reciprocating motion is imparted by the windmill, of a vent valve by which air may escape during a portion of 75 the compressing stroke, and vent closing mechanism operative by contacts between two moving parts relatively adjustable, one of which parts partakes of motion in conformity with the motion of the windmill, 80 while the other moving part receives motion in part through the action of gravitation, whereby the action of said closing mechanism is timed to close said vent valve when the plunger arrives at greater or less distances from the end of its compressing stroke accordingly as the wind increases or diminishes in velocity, substantially as herein set 85 forth.

In testimony whereof I have signed my 90 name to this specification in the presence of two subscribing witnesses.
